CLAIM

The ornamental design for an optical component, as shown and described.

DESCRIPTION

FIG. 1 is a top perspective view of an optical component design;

FIG. 2 is a bottom perspective view thereof;

FIG. 3 is a first side view thereof;

FIG. 4 is a second side view thereof;

FIG. 5 is a top view thereof; and,

FIG. 6 is a bottom view thereof.

UNITED STATES PATENT AND TRADEMARK OFFICE
CERTIFICATE OF CORRECTION

PATENT NO. : Des. 562,494 S
APPLICATION NO. : 29/278015
DATED : February 19, 2008
INVENTOR(S) : Colin Piepgras

Page 1 of 1

It is certified that error appears in the above-identified patent and that said Letters Patent is hereby corrected as shown below:

On the Title Page, Related U.S. Application Data should read

- (63) Continuation of application No. 11/419,995, filed on May 23, 2006, which claims benefit of 60/683,587 filed May 23, 2005, and claims benefit of 60/729,870 filed October 24, 2005, and claims benefit of 60/756,821 filed January 6, 2006, and claims benefit of 60/745,353 filed April 21, 2006 --.

Signed and Sealed this

Tenth Day of June, 2008

JON W. DUDAS
Director of the United States Patent and Trademark Office
